UNITED STATES PATENT OFFICE.

ROBERT D. H. ANDERSON, OF CINCINNATI, OHIO.

OIL-EXTRACTING DEVICE.

SPECIFICATION forming part of Letters Patent No. 738,750, dated September 15, 1903.

Application filed February 2, 1903. Serial No. 141,463. (No model.)

To all whom it may concern:

Be it known that I, ROBERT D. H. ANDERSON, a citizen of the United States, residing at Cincinnati, in the county of Hamilton and 5 State of Ohio, have invented a new and useful Oil-Extracting Device, of which the following is a specification.

My invention relates to improvements in the extraction of oil from exhaust-steam; and 10 the object of my improvement is to furnish pure dry steam for heating systems and steam free from oil for heating feed-water for boilers.

I attain the results desired by the device illustrated in the accompanying drawing.

15 The drawing is a sectional view showing the construction of the entire apparatus in full detail.

The separate parts are all indicated by letters on the drawing.

20 The device is to be constructed of sheet metal, the thickness of which will vary with the size of the extractor.

25 The steam enters the device through the pipe *b* in the center and is discharged against the apex of the cone-shaped center of the upper baffle-plate *U*. The force of the steam striking this cone-shaped center gives it a swirling motion, which causes the oil and condensation to be flung against the under surface 30 of the upper baffle-plate *U* through the agency of centrifugal force. It is held against and caused to traverse along this surface to the trough *W* at the lower edge of the baffle-plate *U* by this same force. When the oil and

35 condensation reach this point, they are caught in the trough *W*, from whence they are drained out through the upper series of drain-pipes *Y* to the lower trough *X*. They are drained from this lower trough *X* through the lower

40 series of pipes *Y* to the bottom of the extractor and are then drained out through the drain-pipe *Z*. It is necessary to place a trap or "gooseneck" somewhere in the line to keep the steam from escaping through it. The

lower baffle-plate *V* catches the steam on the 45 rebound from the upper baffle-plate *U*, and any oil or condensation that may have escaped separation therefrom on its contact with the upper baffle-plate will be deposited on the lower baffle-plate *V* and conveyed to the lower 50 oil-trough *X*, and from thence it follows the course as described above. After the steam leaves the lower baffle-plate it passes between the upper trough *W* and the lower trough *X* and then passes up over the top of the mechanism and out through the flange-opening at 55 the top.

The entire mechanism is held in position by the series of stud-bolts *a a* with nuts and taper washers. (Plainly shown in the drawing.)

What I claim as my invention, and desire to secure by Letters Patent, is—

1. In an oil and condensation extracting device, the combination with the casing, the 65 drain-pipe, *Z*, the inlet-pipe, *b*, the upper baffle-plate, *U*, the oil-trough, *W*, and the upper series of drain-pipes, *Y*, of the lower baffle-plate, *V*, the oil-trough, *X*, and the lower series of drain-pipes, *Y*, substantially as set 70 forth.

2. In an oil and condensation extracting device, the combination with the casing, the drain-pipe, *Z*, the inlet-pipe, *b*, the upper baffle-plate, *U*, the oil-trough, *W*, the upper series of drain-pipes, *Y*, the lower baffle-plate, *V*, the oil-trough, *X*, and the lower series of drain-pipes, *Y*, of the series of stud-bolts, *a a*, and their nuts and taper washers, as and for 75 the purpose shown and described.

In testimony whereof I have signed my name to this specification in the presence of two subscribing witnesses.

ROBERT D. H. ANDERSON.
